No. 624,627.

Patented May 9, 1899.

V. CLARK.

BOILER CLEANER.

(Application filed May 14, 1898.)

(No Model.)

UNITED STATES PATENT OFFICE.

VALENTINE CLARK, OF DRYAD, WASHINGTON.

BOILER-CLEANER.

SPECIFICATION forming part of Letters Patent No. 624,627, dated May 9, 1899.

Application filed May 14, 1898. Serial No. 680,704. (No model.)

To all whom it may concern:

Be it known that I, VALENTINE CLARK, a citizen of the United States, residing at Dryad, in the county of Lewis and State of Washington, have invented a new and useful Boiler-Cleaner, of which the following is a specification.

My invention relates to boiler-cleaning devices, and has for its object to provide a simple, inexpensive, and efficient apparatus adapted for permanent attachment to a steam-boiler and provided with a blade to traverse the bottom or lowermost point of the surface of the boiler in order to enable the operator to draw accumulations of mud and other foreign matter toward a blow-off, the blade being so constructed and mounted that during the forward or operative movement of the apparatus it is rigidly held in the proper position to scrape the surface of the boiler, and during the return or backward movement it is adapted to swing or fold, so as not to push accumulations toward the end of the boiler which is remote from the blow-off.

Further objects and advantages of this invention will appear in the following description, and the novel features thereof will be particularly pointed out in the appended claims.

In the drawings, Figure 1 is a side view of a boiler-cleaner constructed in accordance with my invention applied in the operative position to a boiler, the latter, with the guiding devices for the stem of the cleaner, being shown in longitudinal section. Fig. 2 is a detail view in perspective of the head of the cleaner, including the blade and the contiguous portion of the stem. Fig. 3 is a similar view of the guiding, packing, and blow-off devices. Fig. 4 is a detail sectional view, enlarged, of the stuffing-box and guide.

Similar numerals of reference indicate corresponding parts in all the figures of the drawings.

In the head or tube-sheet 1 of a boiler or similar device from which it is desired to remove accumulations of sediment, scale, &c., is arranged a guide 2, consisting of a three-way or T coupling, of which the aligned arms 3 and 4 are interiorly threaded, the former for engagement with a projecting nipple 5, which forms a fixed part of the boiler-head or

tube-sheet, while connected with the lateral arm 6 is a blow-off pipe 7, having a controlling valve or cock 8. Extending axially through the aligned arms 3 and 4 of the coupling is a cleaner-stem 9, which may be headed at its outer end, as shown at 10, and between which and the walls of the guide leakage is prevented by a suitable stuffing or packing box consisting of a body portion 11, threaded into the bore of the arm 4 and having a packing-seat 12, an adjustable gland-cap 13, threaded upon the exterior surface of the body portion 11 and having a suitable wrench seat or grip 14, and a follower 15, fitted to slide in the packing-seat 12 and flanged, as at 16, for engagement by an interior shoulder 17 of the gland-cap.

The stem 9 may be of sectional construction, with a detachable member 9^a connected with the main or body portion of the stem by means of a union-sleeve 18, and said detachable section is provided with a transverse journal portion 19, terminating in a down-turned stop-arm 20. Mounted upon the journal portion 19 is a blade 21, having a curved operative or outer edge to traverse the interior surface of the bottom of the boiler, and the stop-arm 20 is arranged in the path of the rearward-swinging movement of said blade, whereby during the forward movement of the stem in the direction indicated by the arrow in Fig. 1 said stop-arm holds the blade in operative position to properly scrape the bottom of the boiler and draw accumulations of sediment and scale toward the point of outlet provided by the guide 2 and communicating valved blow-off pipe 7, the diameter of the bore of the arm 3 of the coupling being larger than that of the stem to provide a sufficient annular passage for allowing the sediment thus accumulated contiguous to the blow-off to be forced out through the pipe 7 when the valve 8 is opened. The means illustrated in the drawings for fulcruming the blade 21 upon the journal portion of the stem consists of registering eyes 22; but it will be understood that any equivalent of this construction may be substituted whereby during the return or backward movement of the cleaner the blade is adapted to swing forwardly to the position indicated in dotted lines in Fig. 1, whereby

it may pass freely over material accumulated upon the bottom of the boiler to avoid moving such material toward that end of the boiler which is remote from the blow-off.

- 5 The blade 21 extends laterally beyond the vertical plane of the stem 9, whereby during this backward movement of the cleaner upward-swinging movement of the blade is limited by contact with the stem in the same way 10 that the rearward-swinging movement of the blade during the forward movement of the cleaner is limited by the stop-arm 20.

It will be understood from the foregoing description that an important advantage of 15 the device embodying my invention resides in the fact that accumulations of foreign matter upon the bottom of a boiler or other receptacle (it being understood that the apparatus may be applied to mud-drums and other devices of a like nature) may be drawn toward a blow-off or equivalent outlet, whereby when the valve of such outlet is opened such accumulations may be discharged from the receptacle without withdrawing all of the water therefrom.

Furthermore, the apparatus embodying my invention forms a permanent attachment to the boiler or equivalent receptacle, and the operator by a suitable reciprocation of the 20 stem is enabled to ascertain without reducing the steam whether there are accumulations upon the surface of the boiler which would necessitate blowing off or which, if allowed to remain, would be liable to cause the caking of 25 the sediment and the burning out of the boiler-wall.

Other advantages of the construction dis-

closed will be apparent to those skilled in the art to which the invention belongs, and it will be understood that in adapting the same to 40 receptacles of different kinds various changes in the form, proportion, and the minor details of construction may be resorted to without departing from the spirit or sacrificing any of the advantages of this invention. 45

Having described my invention, what I claim is—

1. A boiler-cleaner having a reciprocatory stem provided with a laterally-offset journal portion and an extension forming a pendent 50 stop-arm, and a blade mounted for swinging movement upon said journal portion of the stem, said stop-arm being in the path of the swinging movement of the blade in one direction, substantially as specified. 55

2. A boiler-cleaner having a reciprocatory stem provided with a perpendicular extension forming a journal portion and a further extension forming a pendent stop-arm, and a cleaning-blade mounted upon said journal 60 portion, and extended in opposite directions beyond the vertical planes of the body portion of the stem and said stop-arm, whereby the forward and rearward swinging movements of the blade are limited, respectively, by the 65 stem and the stop-arm, substantially as specified.

In testimony that I claim the foregoing as my own I have hereto affixed my signature in the presence of two witnesses.

VALENTINE CLARK.
